CLAIM

The ornamental design for an roller bag and workstation, as shown and described.

DESCRIPTION

The present invention is related to presently pending U.S. patent application Ser. No. 17/700,625, filed on Mar. 23, 2022.

FIG. 1 is a perspective view of an roller bag case and workstation showing our new design with handle extended; FIG. 2 is a perspective view of an roller bag case and workstation showing our new design with legs partially extended;

FIG. 3 is a perspective view of an roller bag case and workstation showing our new design with legs fully extended;

FIG. 4 is a perspective view of an roller bag case and workstation showing our new design in an opposing view relative to that shown in FIG. 3;

FIG. 5 is a perspective view of an roller bag case and workstation showing our new design in the same view as shown in FIG. 4 with items separated;

FIG. 6 is a perspective view of an roller bag case and workstation showing our new design in the same view as shown in FIG. 3 with lid open;

FIG. 7 is a perspective view of an roller bag case and workstation showing our new design in the same view as shown in FIG. 6 with drawers open;

FIG. 8 is a perspective view of an roller bag case and workstation showing our new design in an opposing view relative to that shown in FIG. 7;

(Continued)

FIG. 9 is a top view of an roller bag case and workstation showing our new design;

FIG. 10 is a top view of an roller bag case and workstation showing our new design in the same view as shown in FIG. 9 with drawers and lid open;

FIG. 11 is a side view of an roller bag case and workstation showing our new design;

FIG. 12 is a side view of an roller bag case and workstation showing our new design in the same view as shown in FIG. 11 with drawers and lid open;

FIG. 13 is a side view, opposite the side view shown in FIG. 11, of an roller bag case and workstation showing our new design;

FIG. 14 is a side view of an roller bag case and workstation showing our new design in the same view as shown in FIG. 13, with drawers and lid open;

FIG. 15 is an end view of roller bag case and workstation showing our new design; and,

FIG. 16 is an end view, opposite the end view shown in FIG. 15, of an roller bag case and workstation showing our new design.

Any features shown with broken lines are for environmental purposes only and form no part of the claimed design. The design shown is not to be limited to any particular size and may be scaled larger or smaller.
